INFANT'S FOLDING TOILET SEAT

William C. Baxter, Rochester, N. Y., assignor to Trimble Nurseryland Furniture, Inc., Rochester, N. Y., a corporation of New York

Application November 23, 1944, Serial No. 564,771

9 Claims. (Cl. 155—152)

This invention relates to an infant's toilet seat of the general type adapted to be supported on an adult's toilet seat, comprising a folding back and side arms, and has for its object to provide a simple, efficient and practical locking means for holding the back in upright position, secure against accidental displacement.

More particularly, the invention has for its purpose to afford locking means that maintain the back firmly against movement when in upright position, and which can be quickly and easily released to permit folding the back when the seat is not in use.

Another object of the invention is to provide locking means located at one side of the seat, having no parts projecting rearwardly beyond the back edge of the seat or above the top surface of the seat, so as to facilitate packing and prevent likelihood of damage in shipment, while at the same time affording a structure that is of harmonious and pleasing appearance and can be readily manipulated.

An additional purpose of the invention is to afford a hinge plate and locking means that is particularly adapted for use with a folding wooden back which when in upright position extends into close proximity to the upper surface of the seat, while the locking member is entirely concealed, except for its operating portion, behind the hinge plate in a recess in the side edge of the seat in which the locking portion is movable.

Another object of the invention is to afford a construction of economical manufacture that can be readily assembled, and is strong, durable, and effective to accomplish the purpose for which it is intended.

Still a further purpose of the invention is to afford locking means that is conveniently accessible at one side of the seat and can be manipulated by slight pressure to release the back and permit folding the latter.

To these and other ends, the invention consists in the construction and arrangement of parts that will appear clearly from the following description when read in conjunction with the accompanying drawing, the novel features being pointed out in the claims following the specification.

In the drawing:

Fig. 1 is a view in side elevation of an infant's toilet seat constructed in accordance with a preferred embodiment of the invention and illustrating the folding back in upright position;

Fig. 2 is a similar view showing the back in lowered or folded position;

Fig. 3 is an enlarged elevation similar to Fig. 1,

with parts broken away, and illustrating the hinge plate and locking means;

Fig. 4 is an enlarged horizontal sectional view, partially broken away, on line 4—4 of Fig. 3;

Fig. 5 is an enlarged vertical sectional view, partially broken away, on line 5—5 of Fig. 3;

Fig. 6 is a detail view in side elevation of the spring locking plate, and

Fig. 7 is a detail side elevation, partially broken away, of the hinge member.

Referring more particularly to the drawing in which like reference numerals refer to the same parts throughout the several views, 1 designates an infant's toilet seat provided with the usual pins 2 for holding it in proper relation when supported on an adult's toilet seat, 3 designates the back which is hinged to the seat in the manner that will be described presently, while 4 designates side arms pivotally connected to the back 3, and 5 are links pivotally connecting the side arms 4 and the seat 1 to permit folding the back 3 downwardly upon the seat when not in use, in the manner illustrated in Fig. 2.

In the construction shown, the back 3, which is preferably constructed of wood, extends downwardly to a point in close proximity to the top surface of the seat 1, see Fig. 5, and 6 designates one or more resilient bumpers formed of rubber or other suitable material and attached to the lower edge of the back 3 so as to be compressed slightly against the upper surface of the seat when the back is elevated and locked in upright position, thus acting in cooperation with the locking means to hold the back firmly and secure against accidental displacement.

In order to permit swinging the back from folded to upright position and to lock it in such upright position, the back is provided with hinge members or plates at the sides, each of which includes an upper portion 7 having inwardly projecting edge flanges 8 that overlie the front and back surfaces of the back, said upper portion being secured by means of the screws 9, while 10 designates the lower portion of the hinge member having a locking recess 11 at its lower rear portion, and 12 designates a forwardly projecting portion on the hinge plate that is pivotally attached to the seat to permit the necessary swinging movement of the back in relation to the seat.

In order to hold the back in upright position, locking means is provided for locking engagement with the bottom edge 13 of the locking recess 11 in the hinge plate, and to accommodate such locking means, the seat is provided at one side edge

with an inwardly extending recess or pocket 14 within which a locking member is yieldable.

The locking means comprises a spring metal plate including a locking portion 15 and a forward attaching portion 16 that is secured to the side edge of the seat forwardly of the recess and constitutes a bearing surface against which the hinge plate is movable, the hinge plate and locking member being held to the side edge of the seat by a common fastening screw 17 that extends through the hinge plate and attaching portion 16 of the locking member into the seat.

The locking portion 15 of the spring plate is yieldable into the recess 14 and provided with top and bottom laterally extending guiding flanges 18 that engage the top and bottom surfaces of the recess 14, as shown in Fig. 5, to hold the locking member in proper relation and guide its movement, while 19 designates a locking projection formed on the locking portion and arranged to engage the bottom edge 13 of the locking recess 11 in the hinge plate when the back is in upright position and thus hold the back firmly with the rubber bumper 6 compressed between the lower edge of the back and the top surface of the seat.

The outer surface of the locking projection 19 is tapered and bevelled upwardly, as shown in Figs. 5 and 6, to permit the back 3 to be elevated readily during which the hinge plate 10 rides downwardly over the tapered bevelled surface of the locking projection 19, forcing the locking portion 15 inwardly of the recess 14, as shown in dotted lines in Fig. 4, until the locking recess 11 of the hinge plate is coincident with the locking projection 19. Thereupon the locking portion 15 moves back to the full line position of Fig. 4 and projection 19 enters the recess 11 and is held in contact with the lower edge 13 thereof. In this position, the locking projection holds the back firmly and securely in upright position in such a way that it cannot be accidentally lowered, and in order to release the back to permit folding, the locking member is provided with means to facilitate pressing the locking projection 19 inwardly out of engagement with the locking recess 11 in the hinge plate.

This is accomplished by a forwardly extending operating or finger portion that preferably overlies the locking projection 19 and is spaced therefrom. This operating portion is designated at 20 and is connected to the locking portion of the spring plate by a wall 21 which is arranged so as to be flush with the rear edge of the seat. The wall 21 does not project rearwardly beyond the rear edge of the seat, and hence the seat when folded can be packed in a minimum space determined by the outside dimensions of the seat and folded side arms.

When the back is to be folded, the operating portion 20 is pressed toward the side edge of the seat, forcing the yieldable spring locking portion 15 and locking projection 19 inwardly of the recess 14 to the position shown in dotted lines in Fig. 4 until the locking projection 19 is clear of the locking recess 11, whereupon the back 3 can be swung forwardly and folded on to the seat in the manner shown in Fig. 2. This operation can be facilitated by pressing the back slightly rearwardly to compress further the resilient bumper 6 at the same time that operating portion 20 is pressed toward the side edge of the seat, and while this operation is not necessary to the release of the back, it eases the operation by slightly decreasing the resistance to inward movement of the locking member through moving the edge 13 75

of the locking recess in the hinge plate slightly downwardly with relation to the locking projection 19, so that the latter can be pressed more readily away from the hinge plate and into the recess 14.

While the invention has been described with reference to the particular embodiment shown, it is not confined to the details herein disclosed, and this application is intended to cover such modifications or other adaptations as may come within the purposes of the invention and the scope of the following claims.

I claim:

1. The combination with an infant's toilet seat having a recess in one side edge, of a spring member secured to the seat having a locking portion yieldable in said recess and carrying a locking projection thereon, a back, and a hinge member fixed to the back and pivotally attached to said side edge of the seat, the hinge member having an opening engageable with said locking projection when the back is in upright position.

2. The combination with an infant's toilet seat having a recess in one side edge, of a spring member having a locking portion yieldable in said recess and carrying a locking projection thereon and an attaching portion secured to said side edge, a back, and a hinge member fixed to the back and pivotally attached to said side edge of the seat in contact with the spring member for swinging movement thereover, the hinge member having a recess engageable with said locking projection when the back is in upright position.

3. The combination with an infant's toilet seat having a recess in one side edge, of a spring member having a locking portion yieldable in said recess and carrying a locking projection thereon and an attaching portion secured to said side edge at a point forwardly of the recess, a back, and a hinge member fixed to the back and pivotally attached to said side edge of the seat at a point forwardly of said recess in contact with the spring member over which it is movable, said hinge member having a recess the bottom edge of which is engageable with said locking projection when the back is in upright position.

4. The combination with an infant's toilet seat having a recess in one side edge, of a spring member having a locking portion yieldable in said recess and carrying a locking projection thereon and an attaching portion secured to said side edge at a point forwardly of the recess, and a forwardly extending operating portion overlying and spaced from the locking portion and connected therewith by a wall that is flush with the rear edge of the seat, a back, and a hinge member fixed to the back and provided with a forward portion pivotally attached to the seat in contact with said attaching portion of the spring member, said hinge member having a locking recess at its lower rear portion engageable with said locking projection when the back is in upright position.

5. The combination with an infant's toilet seat having a recess in one side edge, of a spring member secured to the seat having a locking portion yieldable in said recess and carrying a locking projection thereon, a back, and a hinge member fixed to the back and pivotally attached to said side edge of the seat, the hinge member having an opening engageable with said locking projection when the back is in upright position, and said locking portion having top and bottom horizontal guiding flanges movable over the top and bottom surfaces of the recess.

6. The combination with an infant's toilet seat

having a recess in one side edge, of a spring member having a locking portion yieldable in said recess and carrying a locking projection thereon, and an attaching portion secured to said side edge forwardly of the recess, and a forwardly extending operating portion overlying and spaced from the locking portion and connected therewith by a wall that is flush with the rear edge of the seat, a back, and a hinge member fixed to the back and provided with a forward portion pivotally attached to the seat in contact with said attaching portion of the spring member, said hinge member having a locking recess at its lower rear portion engageable with said locking projection when the back is in upright position, and said locking portion having top and bottom horizontal guiding flanges movable over the top and bottom surfaces of the recess.

7. The combination with an infant's toilet seat having a recess in one side edge, of a spring member having a locking portion yieldable in said recess and carrying a locking projection thereon, top and bottom horizontal guiding flanges on the locking portion movable over the top and bottom surfaces of the recess, said spring member having an attaching portion, a forwardly extending operating portion overlying and spaced from the locking portion and connected therewith by a wall that is flush with the rear edge of the seat, a back, a hinge member including an upper portion attached to a side edge of the back, a forward portion, and fastening means extending through said forward portion of the hinge member and through the attaching portion of the spring member and holding the hinge member pivotally in contact with the spring member, said hinge member having a locking recess engageable with said locking projection when the back is in upright position.

8. The combination with an infant's toilet seat having a recess in one side edge, of a spring member having a locking portion yieldable in said

recess and carrying a locking projection thereon, top and bottom horizontal guiding flanges on the locking portion movable over the top and bottom surfaces of the recess, said spring member having an attaching portion secured to said side edge forwardly of the recess, a forwardly extending operating portion overlying and spaced from the locking portion and connected therewith by a wall that is flush with the rear edge of the seat, a back having a bottom edge that is spaced slightly above the seat when in upright position, yieldable means attached to said bottom edge of the back and engageable with the upper surface of the seat when the back is in upright position, a hinge member including an upper portion attached to a side edge of the back near the bottom thereof, and a forward portion that is pivotally secured to said side edge of the seat in contact with the spring member and movable thereover, said hinge member having a locking recess at its lower rear portion engageable with said locking projection when the back is in upright position.

9. The combination with an infant's toilet seat having a recess in one side edge, of a spring member having a locking portion yieldable in said recess and carrying a locking projection thereon, top and bottom horizontal guiding flanges on the locking portion movable over the top and bottom surfaces of the recess, said spring member having an attaching portion, a back, a hinge member including an upper portion attached to a side edge of the back, a forward portion, and fastening means extending through said forward portion of the hinge member and through the attaching portion of the spring member and holding the hinge member pivotally in contact with the spring member, said hinge member having a locking recess engageable with said locking projection when the back is in upright position.
